OTTO J. GROEHN AND WILLIAM BLASKEWITZ, OF DETROIT, MICHIGAN, ASSIGNEES TO
CLAYTON & LAMBERT MANUFACTURING COMPANY, OF DETROIT, MICHIGAN, A
CORPORATION OF MICHIGAN.

FIRE-POT CONSTRUCTION.

Application filed January 12, 1925. Serial No. 1,998.

The invention relates to fire pots and refers more particularly to fire pot constructions such as are adapted for plumbers' use or where other uses for oil burning devices of this character are desired.

One of the objects of the invention is to provide a fire pot construction which is of simple construction and readily assembled. A further feature includes the provision of 10 a side feed preventing heat conduction from the burner to the fuel tank. Heretofore, the feed tubes extended directly upwardly from the tank to the burner often requiring the feed tube to be made of an expensive material resisting heat conduction. With our 15 invention ordinary piping may be employed for the feed tube, the arrangement being such as to avoid heat conduction from the burner to the tank.

20 A further feature of the invention resides in provision of an induction chamber having a sediment trap provided with a clean out plug, the arrangement being such that the fuel during its passage to the burner is kept 25 separate from the sediment instead of passing directly through it as is the common construction heretofore. By providing the sediment trap a cheap grade of fuel such as kerosene, or other hydrocarbon, may be employed and at the same time a small jet may 30 be used for the fuel, the sediment trap collecting the foreign matter and carbon deposits of the fuel and preventing clogging of the burner jet.

35 A further objectionable feature in the constructions of fire pots heretofore resided in the fact that after using the fire pots the residue of unburned fuel carbonized in the induction chamber and burner due to the 40 combustion chamber heat. When such fire pots were later used the carbonized fuel interfered with the operation of the burner, clogging the same and otherwise preventing ready passage of clean fuel to the burner. 45 The present invention avoids such difficulties in that the sediment trap collects any carbonized fuel.

A further feature of the invention lies in the provision of a novel handle construction 50 for supporting soldering irons or other tools.

With these and other objects in view, the invention resides in the novel features of construction and combination and arrange-

ments of parts as more fully hereinafter described and claimed.

Referring to the drawings:

Figure 1 is an elevation partly in section showing the fire pot;

Figure 2 is a plan view thereof;

Figure 3 is a detail fragmentary view showing the handle construction when employed for lifting purposes;

Figure 4 is a corresponding view showing the handle in another position when employed as a tool support;

Figure 5 is a plan of the induction chamber and burner, and

Figure 6 is a section along the line 6-6 of Figure 5; the burner being swung into the plane of the section 6-6 for purpose of illustrating the burner in cross section.

In the drawings reference character 10 indicates the tank of a fire pot having the usual filler 10' pump 11 and supporting 75 standard 12 which are secured to the spider 13 carried by the tank 10. The standards 12 removably carry the plate 14 which in turn carries the shield 15 which is removably secured to the pot supports 16 by reason 80 of the overhanging portions 17 thereof.

Carried by the plate 14 at diametrically opposite sides thereof are the lugs 18 having the reduced bearing portions 19 engageable 85 by the slots 20 of the handle 21. The plate 14 is also provided with the hook rests 22 which cooperate with the handle 21 to support the same in substantially horizontal position as shown in Figure 4 for supporting tools while being heated by the burner. 90 When so used the shield 15 is preferably removed by giving to it a partial rotation sufficiently to align the recesses 23 with the supports 16 at which time the shield 15 may be lifted vertically off the plate 14. The supports 16 may receive a pot (not shown) for melting lead and the like.

For carrying the fire pot the handle 21 may be positioned vertically as shown in Figure 3. By reason of the slots 20, in this latter position, the polygonal head 24 enters the correspondingly shaped portions 25 of the handle which prevents swinging of the fire pot relatively to the handle. To place the handle in the horizontal position it is 105 only necessary to allow it to drop vertically sufficiently to free the head 24 from the

portion 25, slots 20 permitting such vertical movement, whereupon the handle may be rotated about the bearing portions 19 into supporting engagement, with the hook rests 5 22.

Extending axially upwardly above the tank 10 is the combustion device comprising the frusto-conical combustion mixing chamber 26 preferably having perforations 27 10 and the induction chamber 28 having the sediment trap 29 normally closed at its lower end with the clean out plug 30 and communicating at a point throughout its length with the fuel feed pipe 31 which extends 15 horizontally away from the induction chamber and is then bent at 90° to extend downwardly into the tank 10. By reason of this construction it will be noted that the feed pipe 31 is positioned to one side and consequently remotely of the combustion chamber 20 and induction chamber. A suitable valve regulable by handle 32 may control the supply of fuel to the induction chamber. The latter chamber communicates at its upper 25 end with a fuel passage 33 leading to the burner 34 provided with the jet 35. The parts preferably have screw threaded engagement as shown to afford ready taking apart for cleaning purposes. The opening 30 35 is axially aligned with the combustion chamber 26.

Supported by the spider 13 is a detachable shield 36 which may surround the burner and combustion chamber.

In operation the fuel passes through the feed pipe 31 into the induction chamber 28 where it is vaporized by the heat from the combustion chamber 26. The vaporized fuel passes through the passage 33 and thence 40 through the burner jet 35, leaving behind in the trap 29 any sediment. The fuel from jet 25 entrains air and combustion takes place within the chamber 26. After use any carbonization caused in the induction 45 chamber will be collected in the sediment trap 29 which may be cleaned by removal of the plug 30. It will also be noted that the fuel does not pass through the sediment trap but is introduced into the induction 50 chamber at a point above the trap. Such provisions affording a clean fuel and unobstructed passages therefor result in a more perfect combustion and permit the use of the small burner jet 35. It will also be noted 55 that a convenient tool rest is afforded by the handle slidably engaging the bearings 19 and adapted to be swung into a horizontal supported position. Furthermore, it will be noted that the fire pot may be readily assembled and disassembled.

While it is believed that from the foregoing description, the nature and advantage of our invention will be readily understood, we desire to have it understood that we do 60 not limit ourselves to what is herein shown

and described and that such changes may be resorted to when desired as fall within the scope of the claims.

What we claim as our invention is:—

1. In a fire pot the combination with a fuel tank and combustion chamber of a combined induction chamber and sediment trap in proximity to but outside of the combustion chamber, and a fuel feed pipe extending upwardly from the tank and provided with a horizontally extending part communicating with the said induction chamber and sediment trap.

2. In a fire pot the combination with a fuel tank and combustion chamber of a vaporizing chamber immediately adjacent the combustion chamber provided with a sediment trap and a fuel feed pipe connecting the tank and vaporizing chamber at a point above the said trap.

3. In a fire pot the combination with a fuel tank and combustion chamber of a vaporizing chamber adjacent the combustion chamber, a burner positioned below the combustion chamber and vaporizing chamber, a communication between said burner and the upper portion of the vaporizing chamber, a sediment trap formed at the lower portion of the vaporizing chamber and a fuel feed pipe between said tank and vaporizing chamber.

4. In a fire pot, the combination with a fuel tank and combustion chamber, of a vertically positioned vaporizing chamber immediately adjacent the combustion chamber, a burner positioned below the combustion chamber, a communication between said burner and the upper portion of the vaporizing chamber, a sediment trap formed at the lower portion of the vaporizing chamber, and a fuel feed pipe between said tank and vaporizing chamber communicating with the latter chamber at a point intermediate the length thereof.

5. In a fire pot the combination with a fuel tank and combustion chamber of a vaporizing chamber immediately adjacent the combustion chamber, a burner positioned below the combustion chamber and the vaporizing chamber, a communication between said burner and the upper portion of the vaporizing chamber, a sediment trap formed at the lower portion of the vaporizing chamber and a fuel feed pipe between said tank and vaporizing chamber communicating with the latter chamber at a point intermediate the length thereof, said fuel feed pipe having a horizontally extending portion communicating with the vaporizing chamber.

6. In a fire pot, the combination with a source of fuel, of a combustion chamber, means for feeding fuel from said source of supply to the burner, said means including a chamber for preheating the fuel and a sedi-

ment trap in the said chamber for collecting sediment and the like from the fuel.

7. In a fire pot the combination with a source of fuel of a combustion chamber, means for feeding fuel from said supply to the burner including means for preheating the fuel and means adjacent said preheating means for removing sediment and the like during the preheating of the fuel.

8. In a fire pot, the combination with a fuel tank, combustion chamber and burner, of a combined vaporizing and sediment removing chamber adjacent the combustion chamber, a fuel feed pipe connecting the tank with the vaporizing and sediment removing chamber, and a conduit connecting the said last named chamber with the burner.

9. In a fire pot, the combination with a fuel tank combustion chamber and burner, of a combined vaporizing and sediment removing chamber in contact with but outside of the said combustion chamber, a fuel feed pipe connecting the tank with the said vaporizing and sediment removing chamber and a conduit connecting said last named chamber with the burner.

10. In a fire pot, the combination with a fuel tank and combustion chamber of a combined vaporizing and sediment removing

chamber adjacent the combustion chamber and a plug removably mounted in the base of the said vaporizing and sediment removing chamber adapted to be removed for giving access to the same.

11. In a fire pot, the combination with a fuel tank, of a combustion chamber arranged above the fuel tank, a vertically positioned vaporizing chamber immediately adjacent the combustion chamber, a fuel feed pipe extending upwardly from the fuel tank and provided with a horizontally extending part communicating with the vaporizing chamber at a point intermediate the ends thereof, a removable sediment trap in the lower end of the vaporizing chamber, and a burner below the combustion chamber, the said vaporizing chamber being provided with a relatively thick wall having a passage extending vertically upward from the said burner, and a second angularly arranged passage for connecting the top of the vaporizing chamber with the said first mentioned passage to permit the passage of fuel from the vaporizing chamber to the said burner.

In testimony whereof we affix our signatures.

OTTO J. GROEHN.

WILLIAM BLASKEWITZ.
